HAIR CURLER

Philip J. Graham, Worcester, Mass., assignor to
Delamere Company, Inc., Jersey City, N. J.,
a corporation of Delaware

Application July 12, 1939, Serial No. 283,975

3 Claims. (Cl. 132—41)

This invention relates to a hair curler of the type comprising a pair of pivotally connected, spring-pressed, cooperating members between which the ends of the hair are engaged and on which it is wound, said cooperating members having associated therewith a swingable clamp member which is adapted to be swung into closed position over the wound hair to keep it from unwinding.

10 The cooperating members of curlers of this type are generally made of metal and are provided with handle portions that extend rearwardly beyond the pivot so as to permit of conveniently opening the two members against the action of the 15 spring. The spring usually consists of a U-shaped leaf, or a wire coiled about the pivot, having its ends bearing against the handle portions.

The principal object of this invention is to provide a construction in which the cooperating 20 members are each made of molded plastic material.

I have found in practice that where the usual type of spring is employed, that is, one having its ends bearing against the handle portions, the 25 handle portions tend to become deformed and bend outwardly by reason of the pressure of the spring.

According to my invention, I overcome this objection by the provision of a U-shaped spring 30 that has its arms directed inwardly and out of contact with the handle portions.

The invention comprises the novel features of construction and arrangement of parts herein-after described and illustrated in the accompanying 35 drawing, in which—

Figure 1 is a side elevation of the curler;

Fig. 2 is a longitudinal section thereof, on an enlarged scale, with the front ends of the cooperating members broken away; and

40 Fig. 3 is a cross-section taken on the line 3—3 of Fig. 2.

The device comprises two cooperating members 10 and 11 each having a handle portion 12 at its rear end. The forward portion 13 of the 45 member 10, upon which the hair is wound, is of cylindrical or slightly tapered tubular form, while the forward portion 14 of the member 10 is of concavo-convex form to fit, in its closed position shown in Figure 1, over the top of the 50 forward portion of the member 10.

The members 10 and 11 of this invention are each formed entirely of molded plastic material. They may be formed in a mold, by any suitable molding or extrusion process, of any suitable 55 molding composition or material, either thermo-

setting or thermoplastic, such for example as cellulose acetate, or plastic resins.

The device is provided with the usual clamp member 15 formed of wire having inturned ends 16 and carrying a roller 17 at its outer end for 5 fastening the clamp in closed position. Other suitable fastening means may be used instead. The inturned ends 16 pivotally connect the members 10 and 11 together, although a separate pivot pin may be used if desired.

The member 11 is formed with ears 18 at its 10 sides adjacent the pivotal point which ears have holes through which the inturned ends 16 of the clamp pass. The member 10 is formed with depressions 19 in its sides into which the ears fit 15 and it has a transverse hole in alignment with the holes in the ears for receiving the inturned ends of the clamp.

The parts and construction heretofore described 20 are all known in the art except for the fact that 20 the members 10 and 11 of the present invention are made entirely of molded plastic material.

In carrying out the present invention, as shown 25 in Figures 2 and 3, I provide the member 11 with an internal recess 20 in the enlarged portion 21 25 in the vicinity of the pivot. The member 10 is likewise provided with a corresponding recess 22 in its enlarged portion 23.

24 is a U-shaped spring having two arms 25 that fit into the recesses 20 and 22, respectively. 30 It will be noted that the bend of the spring faces to the rear and that its arms extend forwardly well beyond the pivotal point of connection of the two members 10 and 11 so as to bear on said members at their enlarged portions.

The lower inner wall 26 of the entrance to the recess 20 and the upper inner wall 27 of the entrance to recess 22 are inclined towards each other, as best seen in Fig. 2, to provide clearance 40 for movement of the spring in opening the members 10 and 11.

What I claim is:

1. In a hair curler of the type described, a pair of cooperating members of molded plastic material pivotally connected together, each having a 45 handle portion protruding rearwardly of the pivot, a U-shaped spring having its arms extending forwardly into recesses in the interior of the cooperating members above and below the pivot, the lower inner wall of the entrance to the upper 50 recess and the upper inner wall of the entrance to the lower recess being inclined rearwardly toward each other.

2. In a hair curler of the type described, a pair of cooperating members of molded plastic mate- 55

rial each having a rearwardly protruding portion, ears on the sides of one of said members fitting into corresponding recesses in the sides of the other and about which said members turn with respect to each other, and a U-shaped spring having arms that extend forwardly into recesses in the interior of the cooperating members and that bear on said members above and below the turning point.

10 3. In a hair curler of the type described, a pair

of cooperating members of molded plastic material each having a rearwardly protruding handle portion, said members having laterally overlapping portions about which they turn with respect to each other, and a U-shaped spring having arms fitting into recesses in the interior of the cooperating members and extending forwardly beyond the overlapping portions thereof. 5

PHILIP J. GRAHAM. 10
